UNITED STATES PATENT OFFICE.

MARTIN T. GRAF, OF BUFFALO, NEW YORK, ASSIGNOR OF ONE-HALF TO FRANK X. IRR, OF BUFFALO, NEW YORK.

KNIFE SHARPENER.

1,417,054.

Specification of Letters Patent. Patented May 23, 1922.

Application filed March 14, 1921. Serial No. 452,197.

To all whom it may concern:

Be it known that I, MARTIN T. GRAF, a citizen of the United States, residing in Buffalo, in the county of Erie and State of New York, have invented new and useful Improvements in Knife Sharpeners, of which the following is a specification.

This invention relates to a knife sharpener which is more particularly designed for sharpening kitchen knives and the like.

It is the object of this invention to produce a sharpener for this purpose which will permit of readily and conveniently putting a keen cutting edge on a knife, either on one or both sides thereof, by drawing the knife one or more times past the sharpening surface of the tool, and so constructing this sharpener that the same can be produced at comparatively low cost, that the same will be safe in use, that the cutting teeth will remain sharp for a comparatively long time and that the cutting teeth of the same will be cleared of chips or metallic dust and therefore not become clogged so that the cutting efficiency is not impaired.

In the accompanying drawings: Figure 1 is an elevation of the preferred form of my improved knife sharpener. Figure 2 is a top plan view of the same. Figure 3 is a vertical longitudinal section thereof, taken on the correspondingly numbered line in Fig. 2. Figure 4 is a vertical transverse section of the same. Figure 5 is a fragmentary horizontal section on an enlarged scale, taken on line 5—5, Fig. 1, and showing the manner in which the blade or knife is engaged with one or the other cutting surfaces of the sharpening tool. Figure 6 is a perspective view of a pair of blades or sharpener sections which together form the sharpening member of the tool. Figure 7 is a fragmentary longitudinal section of one of the sharpening blades, on a greatly enlarged scale, for the purpose of showing the form of the cutting teeth, ribs, ridges, or corrugations.

Similar characters of reference refer to like parts throughout the several views.

The holder of the knife sharpener is preferably constructed of a bar 10 of wood which is substantially rectangular in cross section and of sufficient length so that the end 11 thereof will serve as the handle of the tool, while the other end 12 forms the shank upon which the sharpening devices are mounted.

For this purpose the holder bar is provided on one of its longitudinal edges at the shank end thereof with two notches 13, 13, which open laterally and are separated from each other by an intervening wall or partition 14. 60 The inner transverse side 15 of each of these notches is arranged at right angles to the length of the holder bar while the outer side of each notch has its rear part 16 arranged parallel with the corresponding inner side 65 15, while the front part 17 of this outer side is inclined relatively to the companion rear part thereof, so that the narrow rear part of this notch forms a seat which is of rectangular form in cross section and the 70 front inclined part 17 of the outer side forms a guiding surface against which the knife blade 18 may be rested during the operation of sharpening the same. In each of these notches is arranged a sharpening 75 blade 19 of steel or other suitable material, which blade preferably has a plain inner or rear surface 20 while its outer or front surface is constructed to form a cutting surface over which the edge of the knife blade may 80 be drawn for sharpening the same. Each of these sharpening blades has its rear end engaged with the narrow rear part of one of the notches which forms a seat therefor, so that the rear side of the blade engages 85 with the transverse inner side of the respective notch and the front part of the opposite or cutting surface of the blade is arranged opposite the inclined guiding surface 17 of the respective notch, as best shown in Figs. 1 90 and 3.

The two sharpening blades or sections which together constitute the cutting element of the knife sharpener are held in their respective notches by means which are so 95 constructed that they hold both blades in place at the same time, and thereby simplify the construction of the tool and also effect a considerable economy in the manufacture of the same.

In its preferred construction this fastening device comprises a front washer 21 which engages with the front ends of both sharpening blades, a rear washer 22 seated in a recess 23 formed in the opposite or rear 105 edge of the holder bar and a rivet 24 extending transversely through the partition which separates the notches and engages its opposite enlarged ends with the outer sides of said washers.

110

During the operation of sharpening a knife the blade of the same is alternately drawn lengthwise through the spaces between opposite cutting surfaces of the blades 5 and the inclined guide surfaces of the holder bar, during which operation the blade is rested in a transversely tilted position against these guide surfaces so as to produce the proper bevel upon the cutting edge of the 10 blade. This operation is repeated as often as necessary to produce the desired cutting edge on the blade of the knife.

The cutting surface of each sharpening blade is preferably produced by means of a 15 plurality of parallel cutting teeth, ribs, ridges or corrugations 25 which are arranged on the front side or outer surface of each sharpening blade, the arrangement of these teeth being such that they stand at an obtuse 20 angle relative to the direction in which the knife is drawn past these teeth during the sharpening operation, or in other words, the same lean in the same direction in which the knife is drawn when sharpening the 25 same. By this arrangement of the teeth the cutting action of the same will not be too pronounced and still a sufficient shearing action of the same is obtained on the metal of the knife blade which will produce a sharpening effect on the same, thereby producing a sharpening effect without undue loss of 30 metal and wearing down the knife blade unnecessarily.

In order to further reduce the cutting 35 effect of these teeth, each tooth is so constructed that its front side or face 26 is arranged at an obtuse or steep angle relative to the direction in which the knife blade is to be sharpened is drawn past the same, 40 while the rear side or face 27 of each cutter tooth is arranged at an acute or flat angle relatively thereto, as best shown in Fig. 7. By this means a rearward movement of the 45 knife blade relative to the sharpening surface of each sharpening blade will have no sharpening effect on the same, but upon drawing the knife blade forwardly past the cutter teeth while in engagement therewith the outer edge or corner of each sharpening 50 tooth will produce a mild sharpening or abrading action upon the knife blade which will sharpen the latter without liability of the tooth digging into the metal of the knife blade and unduly wearing the same or producing a roughened surface thereon which 55 otherwise would be the case.

In order to enable the sharpening of the knife blade to be effected by drawing the knife blade in the same direction against both sharpening surfaces of the sharpening 60

blades, the cutting teeth, ribs or ridges of the two sharpening blades which face in opposite directions, are arranged to slope or incline in the same direction and preferably at the same angle, as best shown in Fig. 6. 65 By this means either or both sides of the knife blade can be sharpened by drawing the blade from the front side of the sharpener toward the rear side of the same, thus avoiding improper use of the tool while 70 sharpening a knife blade.

Each of the sharpening blades is preferably narrower than the holder bar and the same is arranged in its respective notch in the holder midway between opposite sides thereof 75 so as to form pockets 28, 28 in the notches adjacent to the opposite longitudinal edges of each sharpening blade, as shown in Figs. 2, 4 and 5. By this means a clearing space is furnished at opposite edges of each sharpening blade into which are discharged the small cuttings, metallic dust or chips removed from the knife blade which is being sharpened, which chips in the absence of such provision would be liable to clog the 80 teeth of the sharpening blades and reduce their efficiency.

As a whole this knife sharpener is very simple and inexpensive in construction and permits of efficiently and quickly putting a 90 keen edge on a knife blade by simply drawing the edge of the same one or more times past the surfaces of the cutting blades in the manner described.

I claim as my invention:

1. A knife sharpener comprising a holder bar which is provided on one side with a laterally opening notch and on its opposite side with a recess, a sharpening blade seated in said notch, a washer engaging with the outer end of said blade, a washer seated in said recess, and a rivet passing through said bar and connecting said washers. 95

2. A knife sharpener comprising a holder bar having two laterally opening notches arranged side by side and separated by an intervening partition, sharpening blades seated in said notches, and a fastening device engaging the outer ends of both of said blades and extending into said partition. 100

3. A knife sharpener comprising a holder bar having two laterally opening notches arranged side by side and separated by an intervening partition, sharpening blades seated in said notches, and a fastening device extending through said partition and engaging with the outer ends of said blades and with that side of said bar opposite to the notches thereof. 115

MARTIN T. GRAF.
